UNITED STATES PATENT OFFICE.

JOHN D. BEATTY, OF IVANHOE, NORTH CAROLINA.

RAILROAD-SIGNAL.

1,225,747.

Specification of Letters Patent.

Patented May 15, 1917.

Application filed May 4, 1916. Serial No. 95,469.

To all whom it may concern:

Be it known that I, JOHN D. BEATTY, a citizen of the United States, residing at Ivanhoe, in the county of Sampson and 5 State of North Carolina, have invented a new and useful Railroad-Signal, of which the following is a specification.

The present invention appertains to railroad signals, and aims to provide a novel 10 and improved mechanism for operating the whistle or other signal of a locomotive in case of emergency or danger, although the invention can be used for operating any suitable signal, or the air brakes or other train 15 stopping means.

The invention includes a device carried by the cab of a locomotive or any other suitable part of a train, and coöperable with a tripping device located upon the track, 20 whereby when the tripping device is set to operating position, the locomotive in passing the tripping device will cause the whistle or signal to give an alarm, thereby warning the engineer and other persons on the 25 train of danger, whereby the train can be brought to a halt to avoid a collision or other accident.

It is also the object of the invention to provide a mechanism of the nature indicated 30 which is extremely simple and inexpensive in construction, which can be readily installed, and which will serve its office in a thoroughly practical and reliable manner.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed can be made within the scope of what is claimed without departing from the spirit of the invention.

The invention is illustrated in the accompanying drawings, wherein:—

Figure 1 is a side elevation of a locomotive showing the present invention applied thereto.

Fig. 2 is an enlarged side elevation of the 50 device.

Fig. 3 is a cross section of the track showing the tripping device.

In carrying out the invention, there is 55 provided a U-shaped hanger 1 having its terminals attached to the bottom of the cab

2 of the locomotive, although the device can be applied to any suitable part of a train, street car, or other vehicle. A rod 3 is slideable through the limbs of the hanger 1 adjacent or upon the lower intermediate portion 60 thereof, and is disposed longitudinally of the track. The forward end of the rod 3 is engaged with one arm of a bell crank lever 4 fulcrumed to a bracket 5 projecting from the forward limb of the hanger 1, and the 65 other arm of the lever 4 is connected by a cord 6 or other suitable connection with the whistle or signal 8, said cord being passed over suitable guide pulleys 7 if necessary. The rod 3 can be connected, however, in various 70 manners to various signals, or can be connected to the air brake system or other train stopping means, whereby when the rod 3 is slid rearwardly relative to the hanger 1, the signal or train stopping means will be 75 operated, which ever is the case. In this connection, the whistle 8 can be taken as typical as representing any suitable signal or train stopping means. A coiled wire expansion spring 9 is disposed upon the rod 3 80 between the hanger 1 and lever 4, to normally move said rod 3 forwardly, whereby the signal or train stopping means 8 is in 85 inoperative position.

A leaf spring or catch 10 is attached to 85 the forward limb of the hanger 1 and bears upon the rod 3, and said rod is provided with an upstanding lug 11 which moves under and in rear of the spring 10 when the rod 3 is moved rearwardly, whereby the 90 spring 10 snaps in front of the lug 11 to hold the rod 3 in rearmost position until released. The rod 3 can be released by a cord 12 or other device attached to the spring 10 and extending into the cab 2, whereby the 95 engineer or attendant can release the rod 3 by pulling the cord 12 so as to remove the spring 10 from the lug 11, whereby the spring 9 will come into play for sliding the rod 3 to its foremost position.

In order that the rod 3 can be pulled rearwardly by a tripping device located upon the track, a curved leaf spring or resilient hook 13 is attached to the rear end of the rod 3 and projects downwardly.

The tripping device located upon the track embodies a transverse rock shaft 14 journaled in bearings 15 secured to one of the cross ties 16, and provided between the rails 17 with an upwardly offset tripping 110

portion 18. One end of the shaft 14 has a crank 19 to which a rod 20 or similar device is connected, whereby the tripping device can be operated from the station, signal 5 tower, or other point to which the rod 20 extends.

In safety or clear conditions, the tripping member 18 is swung downwardly out of the way of the spring hooks 13 of the train devices, but in case of emergency or danger, to avoid a collision or other injury, the tripping device can be brought to operative position through the medium of the rod 20 or other operating means, whereby the tripping member 18 will project upwardly in the path of the hook 13 of a train approaching the point of danger. When the hook 13 engages the member 18, this will retard the rod 3, which will slide rearwardly relative to the hanger 1, thus pulling the cord 6 and blowing the whistle 8. This will notify the engineer and other persons of the danger, whereby the train can be stopped, the rod 3 being held in its rearmost position by the 25 spring catch 10, so that the whistle will continue to blow until the cord 12 is pulled. The hook 13 is resilient or bendable in order that it can spring out of engagement with the member 18 after the rod 3 has been retarded a certain amount.

It is also possible, with the present invention, for trip members similar to the member 18 to be carried by the train, and in case that the train is stopped for any reason whatever, the brakeman or other person can attach one of the tripping members to the track at either end of the train and at a suitable distance therefrom, whereby an approaching train will be given a danger 35 signal.

In some cases, the frame 1 can be applied to the top or sides, or any other suitable point of the cab or car, to coöperate with an overhead tripping device instead of a track 45 tripping device.

Having thus described the invention, what is claimed as new is:

1. A signal mechanism embodying a tripping device, in combination with a train 50 carried reciprocable member having a spring

hook engageable with the tripping device, and a signal controlled by said member.

2. A signal mechanism embodying a rock shaft having an offset tripping member, in combination with a train carried reciprocable member having a spring hook engageable with said tripping member, and a signal controlled by said reciprocable member. 55

3. A signal mechanism embodying a rearwardly slidable member having a spring 60 hook to engage a tripping device, a signal, and means operatively connecting the signal and said member whereby the signal is operated when said member is slid rearwardly.

4. A signal mechanism embodying a frame, a rod slidable therein, and having a spring hook at its rear end engageable with a tripping device, a signal, means connecting said signal and forward end of the rod whereby when the rod is slid rearwardly 70 75 relative to the frame, the signal is operated, and spring means for moving said rod forwardly.

5. A signal mechanism embodying a rod having a resilient hook to engage a tripping device, spring means for moving said rod forwardly, a signal, means connecting said signal and rod whereby the signal is operated when the rod is moved rearwardly, and means for holding said rod when moved 80 rearwardly.

6. A signal mechanism embodying a frame, a rod slidably carried thereby and having a resilient hook to engage a tripping device, spring means for moving said rod forwardly, a signal, means connecting said signal and rod whereby the signal is operated when the rod is slid rearwardly relative to the frame, a catch carried by the frame for holding the rod when moved 90 rearwardly, and means connected to said catch for releasing it from the rod.

In testimony that I claim the foregoing as my own, I have hereto affixed my signature in the presence of two witnesses.

JOHN D. BEATTY.
